UNITED STATES PATENT OFFICE.

ADOLPH RUBIN, OF ST. LOUIS, MISSOURI, ASSIGNOR, BY MESNE ASSIGNMENTS, TO ARCADE MANUFACTURING COMPANY, OF FREEPORT, ILLINOIS, A CORPORATION OF ILLINOIS:

REFRIGERATOR LATCH.

Application filed July 31, 1925. Serial No. 47,291.

This invention relates to refrigerator latches of the general type disclosed in my prior U. S. Patent No. 1,519,267, dated December 16, 1924, which comprise a pivotally mounted retaining element generally referred to as a latch, a handle for disengaging said latch from the keeper and a spring-actuated trigger that moves automatically into engagement with the latch, and thus retains it in an inoperative position when the latch is disengaged from the keeper by manipulating the handle of the lock.

The object of the invention is to provide a refrigerator latch of the particular kind described in my said U. S. patent, which is so constructed that the handle can be easily disconnected from the link that joins the handle to the latch without disconnecting the handle or the latch from the casing.

20 Figure 1 of the drawings is a rear elevational view of a refrigerator latch embodying my present invention; and

Figure 2 is a side elevational view of said latch, with a portion of the casing broken away so as to more clearly illustrate how the padlock and the member through which the hasp of the padlock extends co-operate with the casing to prevent movement of the retaining element or latch.

30 Referring to the drawings which illustrate the preferred form of my invention, A designates the casing of the latch which consists of a hollow casting of substantially oblong shape in general outline provided at one side 35 with a laterally-projecting extension A', B designates the retaining element or latch which is arranged transversely of the casing with one of its ends projecting laterally through the side wall of the casing and its

40 opposite end pivotally mounted in the extension A' on the casing, C designates the keeper that co-operates with the latch B to hold the door in its closed position, D designates the handle which is pivotally connected 45 by a pivot pin 1 to forwardly-projecting lugs 2 on the front wall of the casing and which is provided with an angularly-disposed arm 3, shown in broken lines in Figure 2, that projects into the casing, E designates a link that is attached at its upper end to the arm 3 of the handle and pivotally connected adjacent its lower end by means of a pivot pin 4 to the latch B, as shown in Figure 1, F designates the spring-actuated

trigger that moves automatically into engagement with the latch B, and thus retains it in its elevated or inoperative position when said latch is moved upwardly out of engagement with the keeper C by moving the upper end of the handle D forwardly, 55 5 designates a laterally-projecting tripping device on the trigger that is adapted to engage a stationary abutment adjacent the keeper when the door moves into its closed position, thereby releasing the latch and permitting it to move downwardly into engagement with the keeper and G designates the spring that is combined with the latch B and with the trigger F in such a way that it normally holds the latch in its depressed position and holds the trigger F in readiness to move into engagement with the latch when said latch moves upwardly.

In order that the latch B may be locked in engagement with the keeper C, I provide 75 a member I that is connected with the latch or with some part of the latch operating mechanism and arranged so that the hasp 6 of a padlock J can be inserted through a hole 7 in a portion of said member that is arranged outside of the casing when the latch is in engagement with the keeper. The member I consists of a flat bar connected at its upper end to the link E and arranged with its lower end portion projecting downwardly through a slot in the bottom end wall of the casing A. When the padlock J is not combined with said member I, the latch can be disengaged from the keeper by manipulating the handle D, but when the 80 hasp of the padlock is inserted through the hole 7 of the lower end portion of said member I, said hasp co-operates with the end wall of the casing to prevent upward movement of the member I, thereby securely locking the latch B in engagement with the keeper C, due, of course, to the fact that the member I is attached to the link E of the latch operating mechanism.

In latches of this general character it is 100 frequently necessary to disconnect the handle from the means that is used to transmit movement from said handle to the latch. My improved latch is so constructed that this can be done without dismounting the 105 handle or the part of the latch operating mechanism to which the handle is connected, the casing A being open on one side, as

shown in Figure 1, thus making the cotter key 8 accessible, when the casing is not arranged in operative position on the door of the refrigerator. As shown in Figure 1, the 5 link E is pivotally connected to the angularly-disposed arm 3 of the handle by means of a transversely-disposed pivot pin 9 that is retained in position by a cotter key 8, the portion of the casing of the lock inside of 10 which the arm 3 is arranged being provided in its side wall with a hole 9' so as to permit the pivot pin 7 to be moved laterally out of engagement with the link E and arm 3 after the cotter key 8 has been withdrawn from 15 said pin.

Having thus described my invention, what I claim as new and desire to secure by Letters Patent is:

1. A refrigerator latch, comprising a casing, a latch inside of said casing having a portion projecting outwardly through the casing, a pivotally mounted handle on the exterior of the casing provided with an angularly-disposed arm that projects into the 20 casing, a part that joins said arm with the latch, a pivot pin arranged on the inside of the casing for connecting said arm and part together, and a hole in the casing arranged so that said pivot pin can be moved laterally 25

through the casing out of engagement with 30 said arm and part without dismounting said part or handle from the casing.

2. A refrigerator latch, comprising a casing, a pivotally mounted latch in said casing having a portion that projects outwardly 35 through one wall of the casing, a handle pivotally connected to the exterior of the casing and provided with an angularly-disposed arm that projects into the casing, a link that joins said arm to said latch, a removable pivot pin arranged on the inside of the casing for connecting said link and arm together, an opening in the casing through which said pivot pin can be moved laterally 40 without disconnecting said handle or link from the exterior of the casing, a member inside of the casing attached to said link and projecting downwardly through the lower end wall of the casing, said member having a hole for receiving a locking device 50 that co-operates with the end wall of the casing to retain the latch in engagement with the keeper, and a spring-actuated trigger arranged to automatically engage the latch and hold it in an elevated position 55 after said latch has been disengaged from the keeper.

ADOLPH RUBIN.
